UNITED STATES PATENT OFFICE.

GEORGE T. WILLIAMS, OF DENVER, COLORADO.

SPACE-BAND FOR LINOTYPE-MACHINES.

1,118,718.

Specification of Letters Patent. Patented Nov. 24, 1914.

Application filed February 17, 1914. Serial No. 819,215.

To all whom it may concern:

Be it known that I, GEORGE T. WILLIAMS, citizen of the United States, residing in the city and county of Denver and State of Colorado, have invented certain new and useful Improvements in Space-Bands for Linotype-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in space bands for use in linotype or type casting machines, and is of the class in which two independently adjustable space band members are employed. It may be considered as an improvement on the construction disclosed in my previous application, Serial No. 786,163, filed August 22nd, 1913. In said application the two space band members are independently movable on the body part or member, but they are interlocked in such a manner that a tongue of one part is movable in a groove formed between two tongues of the other part, the last named 30 tongues being movable in a relatively wide, dove-tailed groove formed in the body member.

In my present invention the two independently movable parts of the space band are also independently guided,—that is to say, each member is movable without interlocking engagement with the other member, thus diminishing the friction incident to the adjustability of the said parts, and over- 40 coming any possible tendency for the parts to stick or bind during such adjustment. In a construction of this character, it is important that the space band members move with perfect freedom, so that when the devices which operate to lift them into their spacing position cease to act, the said parts will return by gravity, and consequently automatically, to their normal positions.

As disclosed in the drawing, each independently movable space band member has an independent interlocking connection with the body part of the band. Specifically, each member is interlocked with the body part of the band by a dove-tailed tongue and groove connection.

Having briefly outlined my improved con-

struction, I will proceed to describe the same in detail, reference being made to the accompanying drawing, in which is illustrated an embodiment thereof.

In this drawing,—Figure 1 is a side elevation of a matrix bar of the construction disclosed in my application, Serial No. 786,163, filed August 22, 1913. Fig. 2 is an enlarged view of the lower part of the flexible portion of the bar, between the two lines A and B in Fig. 1, being a view of that part of the matrix bar equipped with the space band features. This view may also be obtained by looking in the direction of arrow 2, Fig. 70. Fig. 3 is a central longitudinal section of Fig. 2, or a section taken on the line 3—3, Fig. 2. Fig. 4 is a view looking in the direction of arrow 4, Fig. 3. Fig. 5 is a central longitudinal section of the construction shown in Figs. 2 and 4, but with one of the space band members in a different relative position. Fig. 6 is a similar view, with the space band members in still a different position from that shown in Fig. 5. Fig. 7 is a detail view of the body part of the space band, equipped with a relatively short, wedge-shaped member. Fig. 8 is a detail view of one of the independently movable space band parts. Fig. 9 is a similar view of the other independently movable part. Fig. 10 is a cross-section taken on the line 10—10, Fig. 7. Fig. 11 is a similar section taken on the line 11—11, Fig. 8. Fig. 12 is a section taken on the line 12—12, Fig. 9. Fig. 13 is a section taken approximately on the line 13—13, Fig. 6. Fig. 14 illustrates a modified form of space band embodying my invention, being adapted for use with the Mergenthaler type of machine. This is a face view of the device, looking in the direction of the arrow 14, Fig. 15. Fig. 15 is a longitudinal section taken on the line 15—15, Fig. 14. Fig. 16 is a view looking in the direction of arrow 16, Fig. 15. Fig. 17 is a sectional view similar to Fig. 15, but showing the independently movable space band parts in different relative positions. Fig. 18 is a detail view of the relatively stationary space band part, of the construction shown in Figs. 14 to 17. Figs. 19 and 20 are elevations of the two independently movable space band parts, respectively.

The same reference characters indicate the same parts in all the views.

Referring first to Figs. 1 to 13, inclusive, let the numeral 5 designate a matrix bar

having a flexible part 6, including a number of members 7, connected by thin metallic parts 8. The lower portion 9 of the flexible part of this bar is equipped with the 5 space band features comprising my present construction. The upper portion of the part 9, or the portion which is intersected by the casting line 10, is equipped with a relatively small, stationary, wedge-shaped part 12 10 which carries a dove-tailed tongue 13 arranged to slide freely in a groove 14 of counterpart shape formed in an independently movable, wedge-shaped space band member 15. The two parts 12 and 15 are so arranged 15 that their thinner extremities are pointed in opposite directions, so that as the movable member 15 engages the stationary member 12, the opposite sides of the co-operating parts 12 and 15 are parallel. On 20 the opposite side of the body part 9 from the member 15 is located a second independently movable space band part 16. This part 16 is provided with two dove-tailed tongues 17 and 18, which move in a groove 19 of counterpart shape formed in the body part 9, the construction being such that the part 16 is movable freely upon the body part 9, and independently of the part 15. The construction is also such that the part 16 and 25 the part 15 may be arranged in co-operative relation, as best illustrated in Fig. 6, without interfering in any manner with each other, the said movable parts 15 and 16 being guided independently of each other and 30 without interlocking relation. When this form of construction is in use, if the wedge-shaped part 15, when arranged in co-operative relation with the wedge-shaped part 12, will perform the desired spacing function 35 40 between the matrix bar members, the part 16 will remain idle, as illustrated in Figs. 2 to 5, inclusive. When, however, the movable space band member 15 is not sufficient to give the desired spacing result, the member 45 50 16 is brought into requisition, as disclosed in Fig. 6, where the three parts 12, 15, and 16 are employed in co-operative relation at the casting line 10 to perform the spacing function. 55 Referring now to the form of construction shown in Figs. 14 to 20, inclusive, let the numeral 20 designate a relatively stationary wedge-shaped space band member, which may be said to constitute the body 60 65 part of the device. As illustrated in the drawing, this part 20 is thickest at its upper extremity, and tapers downwardly. To the lower extremity of the part 20 is secured a tongue 21 which extends from one side thereof. This tongue is of dove-tailed shape, and engages a groove 22 of corresponding shape formed in a movable wedge-shaped space band member 23 which is 70 thickest at its lower extremity, and tapers 75 gradually toward its upper extremity.

This part 23 co-operates with the stationary member 20 to maintain the opposite surfaces of the two parts in parallel relation during the performance of the spacing function. The tongue 21 of the part 20 extends 70 below the lower extremity of the last named part, and on the side opposite from the movable member 23 a dove-tailed tongue portion 24 extends, and interlocks with a groove 25 of counterpart shape formed in a second movable space band member 26. As illustrated in the drawing, the tongue 21 is secured to the part 20 by rivets 27, while the tongue part 24 is secured to the lower portion of the tongue 21 by rivets 28. In 80 describing the operation of this construction, it must be assumed that the wedge-shaped part 20 is stationary, and co-operates with the movable wedge-shaped part 23, their thinner extremities pointing in opposite directions, and the two parts co-operating with each other to maintain the parallelism between their opposite surfaces. When the desired word spacing function can be obtained by the adjustment of the member 90 95 23, the part 26 remains inactive. When, however, a greater spacing function is required than can be obtained by the employment of the part 23 in co-operative relation with the part 20, the part 26 is brought 100 into requisition by moving it upwardly until it crosses or intersects the casting line or area 10, which, as illustrated in the drawing, is between the two horizontal dotted lines in Figs. 3, 5, 6, 15, and 17.

Attention is called to the fact that the member 26 is of uniform thickness except at its upper extremity, which is beveled. In adjusting this member, it is only necessary to move it a sufficient distance to cause its 105 beveled end to pass above the casting line or area 10, since all portions below this beveled end are of uniform thickness, as just explained.

Where this construction is used with the 110 present commercial linotype machine, the space band operating device must be of special construction, whereby it will become practicable to actuate the space band members independently of each other.

In view of the fact that this application is limited to improvements in space bands, it is thought unnecessary to illustrate the space band operating device, which properly belongs to the machine mechanism.

Attention is called to the fact that the body part 9, upon which the space band members are mounted, consists of a thin steel member which is sufficiently flexible to permit the space band member 16, when in its 125 lowermost or normal position, to pass underneath the space band member 15 when the latter is raised to intersect the casting line. This arrangement is illustrated in Fig. 3, in which the member 15 is in the lowest posi- 130

- tion which it can occupy and intersect the casting line, and in this view it will be practicable, in clamping the matrix bars for type casting purposes, to force the member 5 laterally underneath the member 15. Attention is also called to the fact that in the views of this drawing most of the parts are considerably exaggerated in size, in order to make the construction entirely clear.
- 10 Having thus described my invention, what I claim is:
1. A space band composed of a body part and two members adjustable thereon independently of each other, and non-interlocking at all times.
  2. A space band composed of a relatively stationary part and two distinct members adjustable and guided thereon independently of each other, said members being 20 continuously-non-interlocking.
  3. A space band composed of a relatively stationary body part and two continuously-non-interlocking members adjustable thereon independently of each other, each member having an independent interlocking connection with the body part for the purpose of such adjustment.
  4. A space band composed of a relatively stationary body part and two continuously-non-interlocking members adjustable thereon independently of each other, each member having an independent tongue and groove connection with the body part.
  5. A space band composed of a relatively stationary body part and two continuously-non-interlocking members adjustable thereon independently of each other, each member having an independent dove-tailed tongue and groove connection with the body part.
  6. A space band, comprising a relatively stationary part and two continuously-non-interlocking members adjustable thereon in-

dependently of each other, said adjustable members being arranged on opposite sides of the stationary part and guided thereon 45 independently of each other.

7. A space band, comprising a relatively stationary part, and two continuously-non-interlocking members adjustable thereon independently of each other, the two movable 50 members being respectively wedge-shaped and of uniform thickness, and guided on the stationary part independently of each other during such adjustment.

8. A space band composed of a relatively 55 stationary part having a fixed wedge-shaped enlargement intersecting the casting line, a wedge-shaped member movable on the stationary part and coöperating with the fixed wedge-shaped part, and a second member 60 movable on the stationary part independently of the first named movable member, the two movable members being continuously-non-interlocking and guided independently of each other. 65

9. A space band composed of a relatively stationary part having a fixed wedge-shaped enlargement intersecting the casting line, a wedge-shaped member movable on the stationary part and coöperating with the fixed 70 wedge-shaped part, and a second member movable on the stationary part independently of the first named movable member, the two movable members being arranged 75 on opposite sides of the stationary part, continuously-non-interlocking and guided thereon independently of each other.

In testimony whereof I affix my signature in presence of two witnesses.

GEORGE T. WILLIAMS.
